United States Patent Office

Des. 207,421

Patented Apr. 11, 1967

207,421

WEATHER INSTRUMENT

Ellsworth R. Danz, La Salle, and Ralph H. Preiser and David W. Miley, both of Peru, Ill., assignors to General Time Corporation, Stamford, Conn., a corporation of Delaware

Filed June 27, 1966, Ser. No. 2,817

Term of patent 14 years

(Cl. D52—7)

FIG. 1

FIG.2

FIG. 4

FIG. 3

FIG. 5

FIG. 1 is a perspective view of a weather instrument showing our new design as viewed from the front, left thereof;

FIG. 2 is a front elevational view of said instrument;

FIG. 3 is a top, plan view thereof;

FIG. 4 is a right side elevational view thereof;

FIG. 5 is a rear elevational view thereof.

We claim:

The ornamental design for a weather instrument, substantially as shown.
